UNITED STATES PATENT OFFICE.

JOSEPH FELLOWS, OF PHILADELPHIA, PENNSYLVANIA.

DESIGN FOR A CLAMP.

SPECIFICATION forming part of Design No. 33,692, dated December 11, 1900.

Application filed November 17, 1900. Serial No. 36,908. Term of patent 14 years.

To all whom it may concern:

Be it known that I, JOSEPH FELLOWS, a citizen of the United States, residing in Philadelphia, Pennsylvania, have invented and 5 produced a certain new and original Design for a Clamp, of which the following is a specification.

My design for a clamp is clearly illustrated in the accompanying drawing, which represents the clamp in perspective.

The essential feature of the design is the cylindrical shape of the clamp, the flange, and the extended portion below the flange.

10 A is the body of the clamp, having a flange 15 a and a head a'. Below the flange is a series

of ribs b, and below these ribs is an extension d, having a rounded end d'. The said extension is slotted at c, giving the effect clearly illustrated in the drawing.

I claim—

20 The design for a clamp as herein described and as illustrated in the accompanying drawing.

In testimony whereof I have signed my name to this specification in the presence of 25 two subscribing witnesses.

JOSEPH FELLOWS.
